The ornamental design for a childs toy locating device, as shown and described.

DESCRIPTION

FIG. 1 is a top plan view of the childs toy locating device of a first embodiment;

FIG. 2 is a bottom plan view of the first embodiment;

FIG. 3 is a first side elevation view of the first embodiment; the second side elevation of view the first embodiment being a mirror image thereof;

FIG. 4 is a front elevation view of the first embodiment;

FIG. 5 is a rear elevation view of the first embodiment;

FIG. 6 is a top perspective of the first embodiment;

FIG. 7 is a bottom perspective view of the first embodiment;

FIG. 8 is a top perspective view of a second embodiment of our design, the only difference from the first embodiment being that this embodiment includes indicia across an upper surface thereof;

FIG. 9 is a bottom perspective view of a third embodiment of our design, the only difference from the first embodiment being that this embodiment does not include dashed lines; and,

FIG. 10 is a bottom perspective view of the third embodiment.

The dashed lines in FIGS. 2-5 and 7 are environmental structure forming no part of the claimed design of these figures. All surface(s) or portion(s) of the embodiments of our design not shown in the figures or otherwise described in the specification form no part of the claimed design.
